UNITED STATES PATENT OFFICE.

LOUIS KOWITZ, OF LAWRENCE, MASSACHUSETTS.

SAFETY-RAZOR.

1,367,665.

Specification of Letters Patent.

Patented Feb. 8, 1921.

Application filed November 6, 1919. Serial No. 335,981.

To all whom it may concern:

Be it known that I, LOUIS KOWITZ, a citizen of the United States, and a resident of Lawrence, in the county of Essex and State 5 of Massachusetts, have invented an Improvement in Safety-Razors, of which the following description, in connection with the accompanying drawings, is a specification, like characters on the drawings representing like parts.

This invention relates to a safety-razor and has for one of its objects to provide a simple and efficient razor of the character described. The invention further has for 15 its object to provide a razor which is capable of being used after the manner of the safety razors now commonly found on the market or after the manner of the old fashioned razor as will be described.

These and other features of this invention 20 will be pointed out in the claims at the end of the specification.

Figure 1 is a plan view of an inverted safety razor embodying this invention, with 25 the handle shown in section.

Fig. 2, a vertical cross section on the line 2—2, Fig. 1.

Fig. 3, a plan view of the razor shown in 30 Fig. 2.

Fig. 4, a detail of the blade shown in Fig. 1.

Fig. 5, a plan of the blade-supporting member.

Fig. 6, a plan of the blade guard member.

Fig. 7, a longitudinal section on an enlarged scale of the razor shown in Fig. 3, the section being taken on the line 7—7.

Fig. 8, a plan of the razor inverted with the handle arranged for use like the old-fashioned razor, and

Fig. 9, a section on the line 9—9, Fig. 8.

The safety razor herein shown as embodying the invention is provided with a blade-supporting plate or member 10, and with a 45 guard plate or member 12 which are connected together at one end by a pivot pin 13 passed through ears 14, 15, on said members respectively. The supporting member 10 shown separately in Fig. 5 is provided with a projection 16 which is designed to pass 50 through a slot 17 in the blade 18, when the latter is placed upon the supporting member, said projection acting to properly position the blade 18 with relation to the supporting member.

The guard member 12 is also provided

with a slot 19 through which the projection 16 passes to enable the guard member to be brought into engagement with the blade 18 and secure the latter in fixed relation to the 60 supporting member.

The blade 18 is made wider than the supporting member and is provided with cutting edges at its opposite sides which project beyond the sides of the supporting member 65 10 and with which coöperate guards in the form of teeth or fingers 20, extended from the opposite sides of the member 12, and which serve to protect the face from being cut by the blade.

Provision is made for locking the guard member in what may be termed its closed position represented in Fig. 1, and to this end, the guard member has mounted upon it a cam plate or segmental disk 25 which is 75 mounted to turn on a pivot pin 26 and is provided with a thumb piece or handle 27.

The cam plate or disk 25 coöperates with an inwardly projecting lip 28 on the upturned front end 29 of the supporting member 10, to force the free end of the guard member 12 toward the supporting member and to lock the guard member in fixed relation to the supporting member, as represented in Fig. 1.

The blade 18 is provided with inwardly curved ends 30, 31, (see Fig. 4), which enable the blade to be quickly and easily applied to and removed from the supporting member and clear the inwardly projecting 90 lip 28 and at the same time provide the blade with cutting edges of full length as represented in Figs. 1 and 3.

When it is desired to remove the blade, the locking device or cam 25 is turned from 95 under the lip 28 and into substantially the position shown in Fig. 6, whereupon the guard member 12 is free to be turned on its pivot into a position substantially at right angles to the supporting member 10, 100 thereby rendering the blade accessible for removal from the supporting member. When it is desired to assemble the parts for use, the blade is placed over the projection 16 on the supporting member 10 with the 105 guard member in its turned-back or open position. The guard member is then turned down, and the cam turned under the lip 28. The cam 25 and lip 28 are constructed so as to force the guard member against the 110 blade and firmly clamp the latter against the supporting member 10.

The razor is provided with a handle 40 which is detachably secured to the guard member 10, and provision is made for attaching the handle to the guard member so that it may extend at an angle thereto or substantially in the plane thereof, whereby the razor may be used in the manner of the ordinary safety razor, or may be used in the manner of the old-fashioned razor.

10 To these ends, the handle 40 is provided at one end with a threaded socket 41 into which is extended a threaded rod 42 provided with a head 43, which is designed to be engaged with two curved flanges 44, 45, which extend toward each other from end flanges 46 on a substantially semi-circular member 47, which is soldered or otherwise attached to the guard member 12. The inwardly extended flanges 44, 45, form a curved guideway for the head 43 to slide in and these flanges extend transversely of the guard member and terminate at one end away from the guard member a sufficient distance, represented by the space 48, Fig. 2, to permit the ready insertion and removal of the head 43 into and from said guideway.

When the head 43 has been inserted into its guideway, it may be moved therein so as 30 to adjust the handle 40 into different angular positions with relation to the guard member, and when in the desired position, the handle may be turned so as to draw the threaded rod 42 into its socket 41 and thereby cause the head 43 to firmly engage the flanges 44, 45, and secure the handle in fixed relation to the razor.

40 To secure the handle to the razor members so that it extends from one end thereof substantially in the plane of the guard member 12, the end of the handle opposite the head 43 is flattened more or less and tapered and is passed under a bridge member 50, which may be formed by upwardly bending the intermediate portion of the pivot pin 13 (see Fig. 9).

50 Provision is made for frictionally locking the handle to the guard member against accidental removal and for maintaining the handle in a fixed relation to the guard member. To this end the guard member is provided with a spring tongue 52 (see Fig. 7), between which and the guard member 12 the tapered end of the handle is inserted.

55 The tapered end of the handle may be provided with a transverse groove 53 for engagement with a bend 54 in the spring tongue, which parts coöperate to form a lock against accidental removal of the handle. The spring tongue 52 may be formed from the guard member by turning back the portion thereof which is cut to form the slot 19.

60 By reference to Fig. 8, it will be seen that 65 the safety razor may be used in the same

manner as the old-fashioned razor, which is preferred by some users, and with the handle arranged as shown in Fig. 2, the razor may be used like the ordinary safety razor.

Furthermore by making the handle adjustable into different angular positions, the blade may be presented at different angles to the face.

One embodiment of the invention is herein shown, but it is not desired to limit the invention to the particular construction shown.

Claims:

1. In a safety razor, in combination, a blade-supporting member provided at one end with an inturned lip, a guard member pivoted at one end to said supporting member, a rotatable cam mounted on said guard member and coöperating with said lip to lock the said members together, means attached to said guard member for forming a curved guideway extended transversely of the said guard member, and a handle movable in said guideway into different angular positions with relation to said guard member.

2. In a safety razor, in combination, a blade-supporting member, a guard member, a pivot pin connecting said guard member to said supporting member and having an intermediate portion separated from said guard member to leave a space between it and said guard member, and a handle coöperating with said guard member and capable of being inserted between the latter and the intermediate portion of said pivot pin.

3. In a safety razor, in combination, a blade-supporting member, a guard member, a pivot pin connecting said guard member to said supporting member and having an intermediate portion separated from said guard member, a handle coöperating with said guard member and capable of being inserted between the latter and the intermediate portion of said pivot pin, and a spring tongue attached to said guard member and coöperating with the portion of the handle inserted under the intermediate portion of said pivot pin.

4. In a safety razor, in combination, a blade-supporting member, a guard member coöperating therewith and pivoted thereto, means for locking the guard member to said supporting member, a guideway extended transversely of the guard member, a pivot pin for said members having a raised intermediate portion, and a handle constructed and arranged to coöperate with said transverse guideway and with the raised portion of said pivot pin.

5. In a safety razor, in combination, a blade-supporting member provided with an inturned lip at one end and with a blade-engaging projection intermediate its ends, a

- guard member pivoted to said supporting member, a device carried by said guard member for engaging said lip to lock the said members together, means attached to 5 said guard member for forming a curved guideway extended transversely thereof, and a handle provided with a threaded socket and with a threaded rod inserted in said threaded socket and having a head movable in said 10 guideway.
6. In a safety razor, in combination, a blade-supporting member, a guard member coöperating therewith, a handle coöperating with said members, means coöperating with 15 one of said members between its ends for enabling the handle to be extended at an angle with relation to said members, and means coöperating with one of said members at one end thereof for enabling the handle to be extended away from said members 20 substantially in the plane thereof.
7. In a safety razor, in combination, a blade-supporting member, a guard member coöperating therewith, means for securing 25 said members in fixed relation to each other to clamp the blade between them, means attached to said guard member and extended transversely thereof to form a guideway open at one end, and a handle adjustable in 30 said guideway.
- In testimony whereof, I have signed my name to this specification.

LOUIS KOWITZ.
